UNITED STATES PATENT OFFICE.

BENJAMIN E. GETCHELL, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

ELECTRIC SAFETY SWITCH.

Application filed October 30, 1924. Serial No. 746,774.

To all whom it may concern:

Be it known that I, BENJAMIN E. GETCHELL, a citizen of the United States of America, residing at Plainville, county of Hartford, State of Connecticut, have invented a new and useful Electric Safety Switch, of which the following is a specification.

My invention relates particularly to the operating unit for a quick-break switch.

10 The main object is to provide a simple, inexpensive, rugged, and reliable construction.

In the preferred construction the operating handle and concentrically mounted latch mechanism are formed of sheet metal stampings suitably secured together and supported by one side of the box or receptacle containing the switch mechanism.

Figure 1 is a front view of one form of switch embodying improvements of my invention, the cover of the box being open and the protecting fuses being omitted.

Figure 2 is a transverse sectional view of the construction on a larger scale, the box being shown closed.

25 Figure 3 is a side view of the switch mounted in the box body and viewed from the right of Figure 1.

Figure 4 is a side view of the operating unit viewed from the left of Figure 1.

30 Figure 5 is a detail view showing the connection between the hub of the operating handle and the throwing member.

Figure 6 is an extended perspective view of the various parts of the handle, attached 35 latch, hub, and attached latch mechanism.

The particular form of switch mechanism is not material to this present invention but I have illustrated one form for convenience in understanding the operation. The stationary switch contacts 10 and 11 are shown mounted on an insulating base 12. The insulating cylinder 13 carries one or more switch blades 14 and is pivotally supported in the side brackets 15.

45 The switch mechanism is mounted within a box or receptacle having a body 16 and a cover 17, which is conveniently hinged thereto. One side of the box 18 carries the operating unit and latch mechanism. This side

50 18 may be formed separate or integral with the remainder of the box as occasion may require. Preferably this side 18 also carries

a spring catch 19 adapted to project through an opening 20 in the cover and engage an edge thereof to hold the cover closed.

The handle 21 is mounted on the outside of the box and provided with a lost motion connection with a projecting pin 22, which is secured to the cylinder 13 that carries the movable switch members. A series of sheet metal washers or plates, such as 23, 24, 25, 26, 27, 28, 29, 30, and 31 is secured to the handle 21 by means of two rivets 32 which extend through them. The handle is preferably provided with a suitable knob or finger-piece 33 and is also preferably re-inforced by a peripheral flange 34 which houses the washers 23 and 24. The washer 25 serves as a bearing in an opening in one side of the box and is preferably somewhat thicker than the wall of the box so as to allow free movement. The washers 24 and 26 are larger than the washer 25 so that their flanges overlap the edges of the opening in the box around the bearing 25. The washer 23 merely serves as a spacer between members 26 and 29 and 30. The washers 28 and 31 serve as abutments or lateral supports for the member 30.

55 The latch 35 is pivoted to the side 18 of the box and spring pressed toward the latch of plate 26 so as normally to prevent the operation of the latch 26 and attached parts when they are in the position shown in Figures 1 and 4. This latch member 35 has a hook 36 which is adapted to interlock with the pin 37 when the cover is closed. The side of the box is slotted to receive the pin 37 and permit it to engage the inclined shoulder 38 of the latch 35 so as to move the hook 36 into an interlocking engagement with the pin 37 as the cover is closed and disengage the latch 35 from the member 26. The rod 39 is hinged at 40 to the member 30 and is guided in the bracket 41. This rod 39 supports a helical spring 42 which tends to hold the parts in the positions shown in Figures 1, 2, 3, and 4, at which time the lower arm (as viewed in Fig. 4) of the member 30 presses against the pin 22 and holds it in the bottom of the slot 43 in the side bracket 15.

The connection between the operating handle and the member 30 is effected through the pins or rivets 32 and the washer 29,

which latter has notches 44 in its opposite sides for the pins 32. The member 30 has arcuate slots 45 extending through little less than 90°. When it is desired to close the circuit the handle is turned right-handed as viewed from the right of Figures 1 and 2, thus turning the hub together with the pins 32 and swinging the member 30 when the lost motion between the pins 32 and the slots 45 is taken up. When the hinge 40 of the spring rod 39 passes the center-line between the hub and the support 41, the spring 42 throws the member 30 away from this engagement with the handle hub and throws the pin 22 and the contact carrier 13 with its blades 14 into the closed circuit position with a snap-action. In case the spring 42 for any reason has become disabled, the switch can be operated nevertheless by continuing the movement of the handle 21. The circuit is closed by moving the handle 21 in the reverse direction so as to disengage the switch blades 14 from the stationary jaws or contacts 10 and 11 with a snap-action. All the parts will be seen to be very simple to make and assemble, and they have been found to be very rugged and reliable in operation.

I claim:

- 30 1. A switch operating mechanism comprising a plate having a bearing, a bearing washer mounted therein, lateral supporting washers adjacent said bearing washer, a handle having a flanged edge housing the outer washer, a throwing member having a lost motion connection with said handle, and a throwing spring having one end supported by said plate and connected to said throwing member.
- 40 2. A switch operating mechanism comprising a plate having a bearing opening, a bearing washer mounted therein, a latch plate forming an inner lateral supporting washer adjacent said bearing washer, a handle having a flanged edge outside of said bearing washer, a throwing member having a lost motion connection with said handle member, and a throwing spring having one

end supported by said plate and connected to said throwing member.

3. A switch operating mechanism comprising a side plate having an opening, a bearing washer mounted therein, a lateral supporting washer on each side of said bearing washer, a handle having a flanged edge housing the outer washer, a throwing member having a lost motion connection with said handle member, and a throwing spring connected to said throwing member.

4. A switch operating mechanism comprising a plate, a handle, a hub and latch member formed of sheet metal stampings secured to said handle and supported in said side plate, a latch secured to said side plate and co-acting with said latch member, a throwing member having a lost motion connection with said handle, and a spring member connected at one end to said plate and at the other end to said throwing member.

5. A switch operating unit including a plate, a hub having bearings therein and including a washer having notches in its opposite sides, pin members fitting in said notches, and an operating member mounted on said notched washer and having arcuate slots to allow for movement with respect to said pin members.

6. A switch operating unit including a handle, a hub having a bearing, a washer having notches in its periphery, and pin members fitting in said notches and connecting said handle and said washer, and an operating member mounted on said washer and having arcuate slots to allow for movement with respect to said pins.

7. A switch operating unit including a side plate, a hub having a bearing washer therein and including a washer having notches in its periphery, a handle, pin members fitting in said notches and connecting said handle and said notched washer, and an operating member mounted on said notched washer and having slots to allow for movement with respect to said pin members.

BENJAMIN E. GETCHELL.
